(57) **CLAIM**

I claim the ornamental design for a tool chest, as shown and described.

DESCRIPTION

FIG. 1 is a front perspective view of a tool chest;
 FIG. 2 is a top view of the tool chest of FIG. 1;
 FIG. 3 is a front view of the tool chest of FIG. 1;
 FIG. 4 is a rear view of the tool chest of FIG. 1;
 FIG. 5 is a bottom view of the tool chest of FIG. 1;
 FIG. 6 is a left side view of the tool chest of FIG. 1; and,
 FIG. 7 is a right side view of the tool chest of FIG. 1.
 The broken lines showing is included for the purpose of illustrating the environment of the article and forms no part of the claimed design.
